UNITED STATES PATENT OFFICE.

BENJAMIN F. WHEELER, OF DETROIT, MICHIGAN, ASSIGNOR, BY MESNE ASSIGNMENTS, TO THE WHEELER MANUFACTURING COMPANY, OF SAME PLACE.

DESIGN FOR A BICYCLE-SADDLE.

SPECIFICATION forming part of Design No. 34,073, dated February 12, 1901.

Application filed December 26, 1899. Serial No. 741,678. Term of patent 7 years.

To all whom it may concern:

Be it known that I, BENJAMIN F. WHEELER, a citizen of the United States, residing at Detroit, in the county of Wayne, State of Michigan, have invented and produced a new and original Design for Bicycle-Saddles, of which the following is a specification, reference being had to the accompanying drawings, and to the letters of reference marked thereon, which form a part of this specification.

This invention relates to a new and original design for a bicycle-saddle.

In the accompanying drawings, Figure 1 is a perspective view of my design for a bicycle-saddle. Fig. 2 is a plan view thereof. Fig. 3 is a longitudinal section through the design as on line 3 3 of Fig. 2. Fig. 4 is a transverse section through the design as on line 4 4 of Fig. 2.

The leading feature of my design consists in a broad flaring seat portion whose under face is substantially flat in cross-section and presents an unbroken surface and whose upper face is rounding at its margins and curves downwardly, joining the flanged margin of the under face in forming a depending marginal bead, said seat portion having a reduced forwardly-extending pommel slightly tapering and rounded on its upper surface, but flat on its under face, and having a sharp downward curve at its extreme forward end. The rear of the saddle curves sharply upward, so that its extreme edge stands in a plane nearly at a right angle to the upper surface of the saddle.

The rear of the saddle is rounded and at the center is curved inwardly, describing a long even reverse curve. Leading from the inwardly-curved rear portion is an oblong central depression formed in the upper surface only of the saddle, which extends forward to the base of the pommel. The bottom of said depression is substantially flat and without perforation, and the walls thereof on each side incline sharply upward to the surface of the

saddle, which surface curves outwardly and 45 downwardly from said depression to the margin of the saddle on each side. The central depression at the rear margin of the saddle flares outwardly, forming rounded turns.

A designates the rounded seating-surface 50 of the saddle on each side of the central depression B.

C designates the rounded tapering pommel, which stands above the plane of the depression B and is provided with a downwardly- 55 curved nose a and a flat under face I.

D designates the upwardly-turned rear edge of the saddle.

E designates the outwardly-flared portion of the depression communicating with the ob- 60 long portion B and merging into the rear curve of the seat portion. F designates the flat bottom of said depression, and e the upwardly-extending inclined sides thereof. A line of stitching b traverses the central de- 65 pression B and from the outer opening of said depression continues around the margin of the saddle, as shown at c.

G designates the under face, which is sub- 70 stantially flat transversely and extends in a straight horizontal line between the side mar- gins of the saddle, having the depending bead J, and H designates the aprons depend- 75 ing from the opposite sides of the pommel, the whole presenting to the eye an ornate and harmonious figure, as shown in the draw- ings.

Having thus fully set forth my design, what I claim is—

The design for a bicycle-saddle, substan- 80 tially as herein shown and described.

In testimony whereof I sign this specifica- 85 tion in the presence of two witnesses.

BENJAMIN F. WHEELER.
